COMPACT WELDING TORCH CARRIER OR THE LIKE

Daniel E. McCue, Santa Barbara, Calif., assignor to
Cleanweld Products, Inc., Alhambra, Calif.

Filed July 12, 1973, Ser. No. 378,631

Term of patent 14 years

Int. Cl. D8—05

U.S. Cl. D8—71

FIG. 1 is a top plan view of a compact welding torch carrier showing my new design;

FIG. 2 is a side elevational view thereof;

FIG. 3 is a front elevational view thereof; and

FIG. 4 is a rear elevational view thereof.

The carrier is symmetrical about a central vertical plane.

I claim:

The ornamental design for a compact welding torch carrier or the like, substantially as shown and described.
